[57] CLAIM

The ornamental design for a combined vertical sorter and letter tray, as shown and described.

DESCRIPTION

FIG. 1 is a perspective view of a combined vertical sorter and letter tray showing my new design;

FIG. 2 is a top plan view thereof;

FIG. 3 is a bottom plan view of the letter tray;

FIG. 4 is a front elevational view of the combined vertical sorter and letter tray;

FIG. 5 is a rear elevational view thereof;

FIG. 6 is a right side elevational view thereof;

FIG. 7 is a left side elevational view thereof; and

FIG. 8 is an exploded perspective view thereof.
